[57] CLAIM

The ornamental design for a personal message center, as shown and described.

DESCRIPTION

FIG. 1 is a perspective view of a personal message center, showing my new design, shown with the lid partly opened;

FIG. 2 is a left end elevational view thereof, shown with the lid closed;

FIG. 3 is a top plan view thereof;

FIG. 4 is a front elevational view thereof;

FIG. 5 is a rear elevational view thereof.

The bottom of the claimed device is substantially planar and unornamented. The right end is a mirror image of the left end, with the exception of no electrical cord. The conventional electrical cord has been shown fragmentarily in all views for ease of illustration.
